UNITED STATES PATENT OFFICE.

GEORGE E. FERGUSON AND LUIS E. ECKELMANN, OF NEW YORK, N. Y., ASSIGNEES TO
PYRENE MANUFACTURING COMPANY, A CORPORATION OF DELAWARE.

Fire-Extinguishing Agent.

1,421,436.

Specification of Letters Patent.

Patented July 4, 1922.

No Drawing.

Application filed October 23, 1919. Serial No. 332,810.

To all whom it may concern:

Be it known that we, GEORGE E. FERGUSON and LUIS E. ECKELMANN, citizens of the United States, and residents of the city, county, and State of New York, have invented certain new and useful Improvements in Fire-Extinguishing Agents, of which the following is a specification.

The object of this invention is to produce a foam particularly adapted for use as a fire extinguishing agent which has certain new and useful properties which will broaden its application and render its use more extensive and efficient.

15 Foam consists, generally speaking, of a gas trapped or retained in a liquid film, or it may be considered as a dense mass of bubbles. It is obvious that the longer these bubbles can be made to last and the finer the bubbles the better the foam will be for this particular use and the greater will be its application.

20 Using the ordinary reaction of bicarbonate of soda solution and aluminium sulphate solution to produce the carbon dioxide gas, we experimented with various substances to decrease the surface tension of the liquid and increase the surface tension of the foam. As a result of these experiments we found that the use of glue, licorice and saponin gave the best results.

25 Each of these substances, however, was found to have distinctive properties and to produce certain results which made it valuable for this purpose in some respects but not so good in others. Glue gives bubbles, small volume to the foam and, at the same time, renders the foam hard or "dried out;" licorice gives a very slimy, tenacious foam 30 with large bubbles of rather uneven consistency but produces a much larger volume of foam than the glue; saponin gives a much greater surface tension than either the glue or the licorice and seems to advantageously 35 combine the properties of the two and, also, it being a very poisonous colloid, in addition to its property of increasing the surface tension, renders it valuable as a germicide to prevent the growth of organisms in 40 the glue and licorice solutions.

45 We found that by taking the best results from a series of tests, using varying amounts of glue with the same proportions of aluminium sulphate and bicarbonate solutions; 50 the best results from licorice under the same

conditions; and, likewise, the best results from a similar series of experiments using saponin, combining these proportions in one solution and running a similar series of experiments with varying amounts of the combination of these, we finally produced a very homogeneous foam which incorporated the desirable qualities of all three. The proportions which we found to give the best results were as follows:

60 36.3% by volume of a 10% solution of glue.

65 45.4% by volume of a 10% solution of licorice.

70 18.3% by volume of a 10% solution of saponin.

75 We found that the precipitate formed in the reaction between the aluminium salt and the alkali carbonate was, in a large measure, the skeleton body of the foam, the bubbles being lodged in the interstices. Upon microscopical examination, we found that the cellular structure of the aluminium hydroxide which enclosed the bubbles of carbon dioxide gas was not dense enough in body 80 to prevent the bubbles migrating and joining with each other, to the ultimate result of their premature collapsing and consequent destruction of the foam.

85 We realized that if the bubbles could be produced in small form and prevented from changing after formation this difficulty would, in part, be overcome. With this end in view we investigated several salts which have an acid action. The acid value of 90 these salts was determined to be as follows:

Aluminum sulphate, 40.42% H_2SO_4 .

Aluminum chloride, 35.82% HCl.

Copper sulphate, 32.83% H_2SO_4 .

Copper chloride, 38.98% HCl.

95

Ferric chloride, 65.70% HCl.

Ferrous sulphate 36.75% H_2SO_4 .

Ferric sulphate, 66.15% H_2SO_4 .

Manganese chloride, 29.56% HCl.

Zinc sulphate, 33.32% H_2SO_4 .

100

Due to peculiar properties of their water of crystallization, molecular weights and solubilities, certain of these salts eliminate themselves from further consideration in this connection. We found that the hydroxide of iron formed by the reaction:

110 was best suited to our purposes, both as to

the nature of the precipitate and the acidic value of the salt.

Our first line of experiments demonstrated that our alkaline solution was not 5 alkaline enough to compensate for the acidity of the ferric chloride and our precipitate of ferric hydroxide and aluminum hydroxide was not copious enough.

To overcome this difficulty we experienced 10 on the alkaline solution to increase its alkalinity and found that the addition of sodium carbonate to replace a certain amount of the bicarbonate of soda gave us the desired result and the foam was more 15 homogeneous and had a firmer, closer structure.

Microscopical examination showed us that the ferric hydroxide would unite with the aluminum hydroxide to form a denser medium 20 which held the bubbles of carbon dioxide without their changing and obviated the difficulties experienced with the use of aluminum hydroxide alone.

Upon further examination with the microscope 25 we observed that the bubbles after formation and upon exposure to the air seemed to dry prematurely upon the surface and contract, thereby materially reducing the volume of the foam. It was obvious 30 that this was due to the natural moisture of the film evaporating and we found that the addition of a small amount of glycerine to the solutions before mixing prevented this to a large extent, due to the glycerine having 35 the property of retaining moisture indefinitely.

As a result of our experiments we found that the foam which produces the ideal results for the purpose indicated is compound- 40 ed as follows:

An alkaline solution composed of sodium carbonate crystals, 8.83 ozs.; bicarbonate of soda, 1 lb. 10.24 ozs.; water, 12 quarts 6.4 ozs.

An acid solution composed of ferric chloride, 9.07 ozs.; aluminum sulphate, 3 lbs. 5.4 ozs.; water, 4 quarts 25.8 ozs.

To increase the surface tension of the bubbles generated by the mixing of the alkaline and acid solutions we add a small 50 amount of the 10% solution of the glue, licorice and saponin mixture, outlined in the first part of this specification, to either or both of the foam generating solutions. The amount used varies according to the degree 55 of surface tension desired, and other conditions. This can be prepared in solid form to mix with the dry salt, if desired.

We have found that the best results are produced when all three of the said substances 60 (glue, licorice and saponin) are mixed with both of the foam generating solutions but we also found that good results were produced when the same was mixed with only one, preferably the alkaline solution, and, consequently, we do not wish

to be understood as confining ourselves to the particular substances or proportions as herein set out and described as the same represent the result of our experiments which were conducted for the purpose of determining 70 a foam generating medium which would produce a foam more efficient for the purpose of extinguishing fires in which the ordinary foam is not effective, for the reasons hereinbefore set out, and extensive 75 tests with the foam produced according to our invention have shown entirely satisfactory results and have demonstrated its superior sufficiency.

What we claim is:—

1. A fire extinguishing agent, comprising 80 an alkaline solution, an acid solution containing two different salts dissolved in water, and an ingredient adapted when said solutions are mixed to generate a tenacious 85 foam.

2. A fire extinguishing agent, comprising 90 an alkaline solution, an acid solution containing aluminium sulphate and another salt dissolved in water, as an ingredient adapted when said solutions are mixed to generate a tenacious foam.

3. A fire extinguishing agent, comprising 95 an alkaline solution and an acid solution containing aluminium sulphate and ferric chloride dissolved in water, said solutions when mixed being adapted to generate a foam.

4. A fire extinguishing agent, comprising 100 an alkaline solution containing sodium bicarbonate and another salt dissolved in water and an acid compound in solution, and an ingredient adapted when said solutions are mixed to generate a tenacious foam.

5. A fire extinguishing agent, comprising 105 an alkaline solution containing sodium bicarbonate and sodium carbonate dissolved in water and an acid compound in solution, and an ingredient adapted when said solutions are mixed to generate a tenacious foam.

6. A fire extinguishing agent, comprising 110 an alkaline solution containing sodium bicarbonate and sodium carbonate and an acid solution containing aluminium sulphate and ferric chloride, said solutions when mixed being adapted to generate a foam.

7. A fire extinguishing agent, comprising 115 an alkaline solution and an acid solution, each of said solutions containing a plurality of different salts dissolved in water, the salts of the alkaline solution being adapted to compensate the acidity of the salts of the acid solution, and an ingredient adapted when said solutions are mixed to generate a tenacious foam.

8. A fire extinguishing agent comprising 125 an alkaline solution and an acid solution, each of said solutions containing a plurality of different salts and a small amount of glycerine, said solutions when mixed together being adapted to generate a foam.

9. A fire extinguishing agent, comprising an acid and an alkaline solution, said alkaline solution containing glue, licorice and saponin mixed therewith, said solutions when mixed together being adapted to generate a foam.
10. A fire extinguishing agent, comprising an acid and an alkaline solution, each of said solutions containing glue, licorice and saponin mixed therewith, said solutions when mixed together being adapted to generate a foam.
11. A fire extinguishing agent, comprising an alkaline solution containing sodium carbonate and sodium bicarbonate, an acid solution containing ferric chloride and aluminum sulphate, and glue, licorice and saponin mixed with each of said solutions.
12. A fire extinguishing agent, comprising a solution of sodium carbonate and sodium bicarbonate, a solution of ferric chloride and aluminum sulphate, said solutions also containing glycerine, glue, licorice and saponin mixed therewith.
13. A fire extinguishing agent comprising an acid solution and an alkaline solution, one of said solutions containing licorice.
14. A fire extinguishing agent comprising an acid solution and an alkaline solution, one of said solutions containing licorice and saponin.
15. A fire extinguishing agent comprising an acid solution and an alkaline solution, one of said solutions containing a colloid, a surface-tension-increasing liquid of vegetable origin, and a viscous substance of organic origin adapted to produce a tenacious foam.
16. A fire extinguishing agent comprising an alkaline solution and a solution of a plurality of acid salts of different acid values, said solutions when mixed forming a foam and producing a plurality of precipitates corresponding to the plurality of acid salts, said plurality of precipitates forming a medium of more suitable density for holding the bubbles of foam than is formed by the precipitate of any of said acid salts alone.
17. A fire extinguishing agent comprising an alkaline solution and a solution of a plurality of acid salts of different acid values, said solutions when mixed forming a foam and producing a plurality of precipitates corresponding to the plurality of acid salts, said plurality of precipitates forming a medium of more suitable density for holding the bubbles of foam than is formed by the precipitate of any of said salts alone, and a substance for decreasing the surface tension of the liquids.
18. A fire extinguishing agent comprising a solution of an alkaline salt and a solution of an acid salt, said solutions when mixed forming a foam and producing a precipitate, said acid solution containing an additional acid salt to produce an additional precipitate forming a medium of more suitable density for holding the bubbles of foam than is formed by the precipitate of either of said acid salts alone, said alkaline solution containing an additional alkaline salt to compensate for said additional acid salt.
19. A fire extinguishing agent comprising a solution of sodium bicarbonate and sodium carbonate and a solution of aluminum sulphate and ferric chloride, said solutions when mixed forming a foam and a precipitate of aluminum hydroxide and ferric hydroxide, said combined precipitate forming a better medium for holding the bubbles of foam than the aluminum hydroxide alone, said sodium carbonate serving to neutralize the ferric chloride.

Signed at the city, county and State of New York, this 16 day of October, 1919.

GEORGE E. FERGUSON.
LUIS E. ECKELMANN.

DISCLAIMER.

1,421,436.—George E. Ferguson and Luis E. Eckelmann, New York, N. Y. FIRE-EXTINQUISHING AGENT. Patent dated July 4, 1922. Disclaimer filed August 24, 1923, by the assignee, Pyrene Manufacturing Company.

Hereby enters this disclaimer—

“To that part of the claim (numbered 13) in said specification which is in the following words, to wit:

“13. A fire extinguishing agent comprising an acid solution and an alkaline solution, one of said solutions containing licorice.”
